UNITED STATES PATENT OFFICE

121,788

DESIGN FOR A TEXTILE FABRIC

Alfred J. Heinke, Paterson, N. J., and Arthur Kahn, New York, N. Y., assignors to Oshkosh Trunks, Incorporated, Oshkosh, Wis., a corporation of Wisconsin

Application April 22, 1940, Serial No. 91,876

Term of patent 14 years

To all whom it may concern:

Be it known that we, Alfred J. Heinke and Arthur Kahn, citizens of the United States and residents respectively of Paterson, in the county of Passaic and State of New Jersey, and New York, in the county of New York and State of New York, have invented a new, original, and ornamental Design for a Textile Fabric, of which the following is a specification, reference being had to the accompanying drawing forming part thereof.

The figure is a plan view of a textile fabric showing our new design.

We claim:

The ornamental design for a textile fabric, substantially as shown.

ALFRED J. HEINKE,
ARTHUR KAHN.
